H. L. DEXTER

Des. 171,845

PUPPET OR SIMILAR ARTICLE

Filed Dec. 21, 1953

FIG. 2

FIG. 1.

INVENTOR

Herbert L. Dexter.

BY *Arthur D. Stewart*

ATTORNEY

UNITED STATES PATENT OFFICE

171,845

PUPPET OR SIMILAR ARTICLE

Herbert L. Dexter, Philadelphia, Pa., assignor to
Westinghouse Radio Stations, Inc., a corpora-
tion of Indiana

Application December 21, 1953, Serial No. 28,165

Term of patent 14 years

(Cl. D34—2)

To all whom it may concern:

Be it known that I, Herbert L. Dexter, a citizen of the United States, residing in Philadelphia, State of Pennsylvania, have invented a new, original, and ornamental Design for a Puppet or Similar Article, of which the following is a specification, reference being had to the accompanying drawing, forming a part hereof, in which:

Fig. 1 is a front elevational view of a puppet embodying my design; and

Fig. 2 is a side elevational view thereof.

I claim:

The ornamental design for a puppet or similar article, as shown.

HERBERT L. DEXTER.
